(57) CLAIM

The ornamental design for a bed, as shown and described.

DESCRIPTION

FIG. 1 is a perspective view of a bed showing my new design;

FIG. 2 is a front view thereof;

FIG. 3 is a front view inside the headboard;

FIG. 4 is a front view of the footboard; and,

FIG. 5 is a side view, the opposite side being a mirror image thereof.

The broken lines in FIG. 3 are for illustrative purposes only and form no part of the claimed design.

1 Claim, 5 Drawing Sheets

FIG. 2

FIG. 3

FIG. 5
